UNITED STATES PATENT OFFICE.

WILLIAM L. DOLBEARE, OF WEST NEWTON, MASSACHUSETTS.

FLOOR.

SPECIFICATION forming part of Letters Patent No. 258,900, dated June 6, 1882.

Application filed April 3, 1882. (No model.)

To all whom it may concern:

Be it known that I, WILLIAM L. DOLBEARE, of West Newton, of the county of Middlesex and State of Massachusetts, have invented a new and useful Improvement in Floors; and I do hereby declare the same to be described in the following specification and represented in the accompanying drawings, of which—

Figure 1 is a top view, and Fig. 2 a transverse section, of a floor constructed in accordance with my invention, the nature of which is defined in the claim hereinafter presented.

The object of my invention is the production of a floor that shall be water-proof.

In carrying out my invention I lay on, in the usual manner and next to the flooring-timbers C, a course of boards, B B, and upon such course I arrange and fasten down by nails another of planks, A, such being so that the joints between the boards B B of the foundation-course shall be broken or lapped over, or covered by the planks A. Furthermore, the several planks I arrange at short distances apart—that is to say, so that each shall not touch at its edge or edges that or those immediately next to it—and I groove each plank near or rabbet it at the lower part of each edge of it, as shown at a. Into the spaces between the planks I pour fillings b, consisting of a heated liquid composition of tar and pitch in or about in equal proportions, or such as when the composition may become cool will cause it to be sufficiently elastic or non-frangible. The composition used should possess the qualities of being elastic, adhesive, and water-proof—that is to say, it

should be adhesive in order to cause it to firmly adhere to the planks and the boards B, where directly under it, and should be elastic to admit of it (as the planks may shrink or swell) yielding laterally without materially affecting 40 its adhesion to them, and it should be water-proof in order to prevent water, when on the upper surface of the flooring, from passing down between the planks to their supporting-boards, or getting between such boards and 45 planks.

I am aware that the planks of a deck or side of a ship are usually calked in their seams, oakum and tar being used for such purpose. Such planks, however, have not been grooved 50 or rabbeted for the purpose of keeping in place the calking.

I am also aware that pavement-blocks have been notched on their edges to receive cement run between them and the next adjacent blocks. 55 I therefore make no claim to such, my invention relating to floors only.

I claim—

A water-proof floor, substantially as described, composed of the foundation-timbers 60 c, the covering-course of boards B, the superimposed course of grooved or rabbeted planks A, and the elastic, adhesive, and water-proof composition fillings b, arranged and combined essentially as explained.

WILLIAM L. DOLBEARE.
